UNITED STATES PATENT OFFICE.

FRANCIS LOUIS TRINCA, OF CAULFIELD, VICTORIA, AUSTRALIA.

APPLIANCE FOR ASSISTING CHILDBIRTH.

Application filed December 2, 1924. Serial No. 753,511.

To all whom it may concern:

Be it known that I, FRANCIS LOUIS TRINCA, a subject of the King of Great Britain, residing at No. 96 Balaclava Road, 5 Caulfield, in the State of Victoria and Commonwealth of Australia, have invented a new and useful Appliance for Assisting a Childbirth, of which the following is a specification.

10 In the course of evolution, change of posture from the four-footed to the erect attitude has greatly interfered with the process of child-birth. In four-footed animals, the animal delivers itself on all fours, or on its 15 knees. In this manner the muscles, which expel the offspring, operate against the purchase of a rigid vertebral column, and also gravity. When a patient lies on a bed, this 20 mechanical advantage is lost. During child-birth, the usual aids extended are allowing the mother to pull on a towel attached to the head of the bed, or pressure is applied by hand to the lumbo-sacral region. Each aims 25 at restoring the rigid vertebral column, and so restoring the requirements of evolution. The pressure applied by hand is of the greatest benefit, but is too exhausting to the operator to be continued for any length of time.

30 The object of the present invention is to provide an appliance by means of which pressure can be applied by the patient herself to her lumbo-sacral region during each recurring labour pain.

35 Referring to the drawings hereto annexed:—

Figure 1 is a side elevation of my appliance for assisting child-birth;

Figure 2 is a front elevation thereof;

40 Figure 3 is a back elevation thereof;

Figure 4 is a side elevation of the lower portion of the appliance (illustrated in Figure 1) in engagement with the left-hand angle iron (shown in section) of an iron 45 bedstead;

Figure 5 is a front elevation of Figure 4;

Figure 6 is a side elevation of the lower 50 portion of the appliance (illustrated in Figure 1) in engagement with a short length of angle iron (shown in section) affixed to the left-hand side rail (also in section) of a round frame hospital bedstead;

Figure 7 is a front elevation of Figure 6;

55 Figure 8 is a side elevation of the lower portion of the appliance (illustrated in Figure 1) in engagement with a short length of

angle iron (shown in section) affixed to the left-hand side rail of a wooden bedstead;

1 is a vertical bar of spring steel, the lower end of which is re-curved to constitute a 60

U-shaped recess 2 to receive or engage either with the vertical portion 3 of the left-hand angle iron of an iron bedstead, or with the vertical portion 4 of a short length of angle iron affixed either to the left-hand rail of a 65 wooden bedstead or to the same rail of a round frame hospital bedstead. By "left-hand angle iron" or "left-hand rail" is meant that angle iron or rail which is on the left of an observer standing at the foot of the bedstead. 5 is a threaded bolt inserted in a slot provided in the bar and in turn fitted with a butterfly nut 6 by operating which the vertical bar is held firmly to the vertical portion 3 of the angle iron of an iron bedstead. 7 is a short vertical slot in said 70 vertical bar 1, said slot being situated immediately above the recess 2. 8 is a threaded bolt which passes through said slot 7. Said bolt is provided with a hook 9 at one end, 75 to engage with the horizontal portion 10 of the angle iron. 11 is a butterfly nut at the other end of bolt 8, by operating which the necessary adjustment and attachment of the appliance to the bedstead can be effected. 12

80 is a long vertical slot in the said vertical bar 1. 13 is the vertical portion of an L-shaped metal bracket. 14 is a T-piece at the upper end of said vertical portion, the ends 15 of said T-piece being bent to engage 85 with the respective edges of the said vertical bar 1, so as to permit of said bracket sliding 90 freely up and down on said vertical bar. 16 is a threaded bolt which passes through the vertical portion 13 of said L-shaped bracket, and also through the said long vertical slot 12. 17 is a butterfly nut on the end of said bolt 16, by operating which the L-shaped bracket can be raised or lowered, 95 as may be required. 18 is the horizontal portion of said L-shaped bracket which at its outer end is attached by means of a ball and socket joint 19 to an oval-shaped metal plate 20, to the front of which is attached, in any approved manner, a pad 21 of sponge rubber. 22 are two pins which project outwardly from what constitutes the back of the vertical bar 1. 23 is a strap of webbing having a loop 24 at one end, which loop 100 engages with the vertical bar 1 between the said pins 22. 25 is a buckle on said strap 23, 105 and 26 are eyelets at the other end, with

95

100

105

110

which said buckle can engage, if required, so as to constitute a loop at the end of the strap. 27 is a short length of angle-iron which I use when it is desired to attach my 5 appliance to a wooden bedstead, or a round frame hospital bedstead. This short length of angle iron 27 is affixed to the left-hand side rail of the bedstead, as illustrated in Figure 7, by means of bolts 28 which pass 10 through holes 29 in the said side rail, any side slip being prevented by the slot 30 with which the U-shaped recess 2 engages.

When my appliance is attached to a bedstead, the patient lies on her left side with 15 the pad 21 against her lumbo-sacral region. The strap 23, one end of which, as before explained, is attached to the top of the flexible steel bar 1, is then passed between her right arm and body, and the free end 20 of the strap is grasped by her with both hands. At each recurring labour pain, she pulls on the strap 23, thus causing the upper end of the flexible steel bar 1 to yield. In lieu of pulling on the end of the strap 23, 25 the said end may be formed into a loop, by causing the end of the strap to engage with the buckle 25, and the right arm of the patient passed therethrough, thereby permitting of greater traction on the vertical bar 1. The result, in either case, is that the 30 necessary pressure is exerted on the lumbo-sacral region. The use of my appliance results in greatly decreased pains, as felt by the patient: reflex quickening and increased 35 efficiency of the pains expelling the foetus; and diminution of the final exhaustion of the patient and its dangers. There is also a probable increase in size of the bony outlet, due to rotation of the iliac bones around 40 the ileo-sacral synchondroses allowed by a bending of the symphysis pubes.

I claim:—

1. An appliance of the character described comprising a vertically mounted bar

of spring steel, a bracket adapted to be 45 secured in various positions of vertical adjustment on the bar, a pressure applying member connected to the bracket, and a pulling member connected to the upper end 50 of the vertical bar whereby pressure is applied to the pressure member, substantially as and for the purposes set forth.

2. An appliance of the character described comprising a vertical bar of spring steel provided with a slot, a bracket, means 55 connected with the bracket and slidably mounted in the slot in the bar for releasably clamping the bar in various positions of vertical adjustment on the bar, a padded pressure applying member universally connected to the bracket, and a flexible pulling member attached to the upper end of the bar for transmitting pressure to the pressure applying member.

3. An appliance of the character described comprising a vertical bar of spring steel the lower end of which is curved to provide a U-shaped recess while the portion immediately above the recess is provided with a vertical slot, a hook like clamping bolt adjustably mounted in the slot, a clamping element mounted on the bolt, the vertical bar being also provided with another vertical slot in the upper portion thereof, an L-shaped bracket the top of the vertical portion of which engages with the vertical bar and is adapted to slide vertically thereon, a metal plate universally connected to the end of the horizontal portion of the bracket, a pad connected to the outer side of said plate, a nut and bolt arrangement engaged by the bracket and upper slot for holding the bracket in various positions of vertical adjustment, and a flexible pulling member attached to the vertical bar, substantially as and for the purposes set forth.

FRANCIS LOUIS TRINCA.
